UNITED STATES PATENT OFFICE

EDWIN A. OLLEY AND DANIEL B. WINTER, OF SYRACUSE, NEW YORK, ASSIGNORS TO CROUSE-HINDS COMPANY, OF SYRACUSE, NEW YORK, A CORPORATION OF NEW YORK

FASTENER FOR BOXES

Application filed January 30, 1929. Serial No. 336,278.

This invention relates to fastening means for securing covers on boxes and the like and more particularly for securing the trim on a panel board cabinet or boxes. The fastening means is of the kind shown in Greaves Patent No. 1,287,000 issued December 10, 1918.

The invention consists in the novel features of construction whereby the cost of manufacturing is greatly reduced. Other advantages will appear upon reading the following description.

In describing this invention reference is had to the accompanying drawings in which like characters designate corresponding parts in all the views.

Figure 1 is an inverted plan view showing a portion of the trim with contiguous portion of the cabinet partly in section.

Figure 2 is a view in elevation of the clamping means shown in operative position securing a portion of the trim to the contiguous portion of the cabinet.

Figure 3 is a view in elevation similar to Figure 2 with the fastening means in inoperative position.

1 designates the side walls of the panel board cabinet or box and 2 a flange formed on the front of the box by the walls being turned inwardly, which flange provides a support for the trim 3. The trim in this instance corresponds to the cover of a box.

The fastening means here shown is carried by the cover or trim which is secured in position after the box or cabinet is placed in operated position, generally in the walls or partitions of buildings.

4 designates an S-shaped support with a central elongated portion formed at right angles to the parallel end portions. One end portion is secured to the under side of the trim, preferably by spot welding, while the other is drilled to receive the end of a screw 5.

6 is a jaw or clamping member formed from a flat piece of steel by bending over the sides forming a channel with a back portion 7 and side rails 8.

The side rails are shaped similar to a jack knife blade with the heel portions drilled and threaded to receive the screw 5.

In assembling the device, one end portion of the support 4 is spot welded to the trim in a predetermined position. The screw 5 is then passed through a hole in the trim, also at a predetermined position in relation to the support 4 so that the screw 5 will pass through the hole formed in the opposite end portion of the support 4. After the screw 5 is passed through the hole in the trim 3, it is threaded through the heel portions of the jaws 6 and then passed through the hole in the end portion of the support 4 and headed over, as shown at 9, so that the screw cannot get out of place and cause trouble and delay when the trim is being secured in position on the front side of the box or cabinet.

Upon turning of the screw 5 in a clockwise direction, the jaw 6 is caused to move in the same direction as the screw until the rear edge portion 10 contacts with the central portion of the support 4, at which time, the outer end of the jaw assumes an operative position under the flange 2 of the box or cabinet.

Continued turning of the screw 5 causes the jaw 6 to move toward the trim and eventually engage with the flange 2 of the box or cabinet, thus clamping the trim 3 tightly on the front of the cabinet. Generally the screw 5 will fit the threaded portion of the side rails 8 of the jaw 6 tight enough to cause the jaw to move with the screw until stopped by contact with the central portion of the support 4. However, to prevent the jaw 6 from becoming loose, the screw 5 is provided with tension means as shown by spring 10^a which holds the jaw in frictional contact with the screw throughout its entire length. To compensate for the thickness of the spring when compressed, and also to render the clamping means more effective, a boss or raised portion 11 is provided on the end portion of the upper side rail of the jaw 6 which raised portion coacts against the flange 2 of the box or cabinet.

In operation, the fastening means is so placed upon the trim that by turning the screw counterclockwise and thus turning the jaw member 6 in the same direction, the

jaw assuming a position out from under the flange 2. The trim is then placed upon the front of the box or cabinet and by merely turning the screw 5 in clockwise direction, the end of the jaw 6 is swung under the flange 2 and by continued movement of the screw, the jaw is caused to slidably engage with the central portion of the support 4 and eventually coat against the flange 2 as heretofore described.

10 What we claim is:

1. A clamp comprising a support, a screw secured to said support to prevent endwise movement of the screw, a jaw threaded on the screw, and means to limit the rotary movement of the jaw by contact with the support.

2. The combination of two parts to be clamped together, a clamp comprising a support carried by one part, a screw extending through said part and into engagement with the support, and means for holding the screw from endwise movement, a jaw threaded on the screw and slidably engaging the support and means for holding the jaw in sufficient frictional contact with the screw whereby the jaw is rotated with the screw until stopped by contact with the support.

3. The combination of a box and a cover to be clamped together, a support carried by the cover on the inner side thereof and depending into the box in a general direction parallel to a side wall of the box, a screw extending through the cover substantially parallel to the depending portion of the support and connected to the support at its inner end to hold the screw from displacement, a jaw threaded on the screw, the screw extending through the jaw near one end thereof and said end slidably engaging the support and having a shoulder to coat with the support when the jaw has been turned to position in operative relation to the wall of the box.

45 In testimony whereof, we have hereunto signed our names at Syracuse, in the county of Onondaga and State of New York, this 25th day of January, 1929.

EDWIN A. OLLEY.
DANIEL B. WINTER.
